UNITED STATES PATENT OFFICE.

PAUL J. HACKETT, OF SEATTLE, WASHINGTON, ASSIGNOR TO UNIVERSAL HIGH POWER
TELEPHONE COMPANY, OF KING COUNTY, WASHINGTON.

SOUND-AMPLIFYING DEVICE.

1,149,822.

Specification of Letters Patent. Patented Aug. 10, 1915.

Application filed July 6, 1914. Serial No. 849,275.

To all whom it may concern:

Be it known that I, PAUL J. HACKETT, a citizen of the United States, and a resident of Seattle, in the county of King and State of Washington, have invented certain new and useful Improvements in Sound-Amplifying Devices, of which the following is a specification.

This invention relates to sound amplifying devices and has for its principal object to provide means for amplifying the movement of a diaphragm, with a minimum of resistance and friction due to the weight and inertia of the moving parts, and also to provide means for regulating the amount of amplification of a diaphragm.

I attain these objects by the mechanism illustrated in the accompanying drawings, described in the following specifications and pointed out in the appended claims.

In the drawings, Figure 1 is a plan view of my device, with certain parts broken away. Fig. 2 is a side elevation, partly in section.

Referring now more particularly to the drawings, reference numeral 1 designates a permanent magnet of the usual type, having a coil 2, with pole tips 2^a, an armature 3 one end of which rests upon one pole of the magnet, being held in place by lugs 1^a which project from the magnet. The other end of the armature is drawn to the pole tips 2^a of the coil by the attraction of the magnet. A spring 4, having a slot 4^a down its center to admit the wire 5 to pass through it, bears against the armature and thereby assists the attraction of the magnet to hold the armature to the magnet, the said spring having adjusting screws 4^b and being secured to frame pieces 6 which are secured to the magnet by the bolts 7 and nuts 7^a, thus forming a support to which is secured a block 8 by means of screws 8^a. Attached to the said block, by screws 8^b, is a frame piece 6^a. Through an aperture 9 in the block 8 a pin 9^a is adjusted to slide under the action of an adjusting screw 10 which has a head 10^a which bears against the block 8, thereby retaining the pin 9^a. One end of the wire 5 is attached to the inner ends of the said pin and the other end of the said wire is attached to the armature at 5^a. Resting on outstanding members 6^b and secured to the upper frame pieces 6 and 6^a, by means of the screws 11, is a circular diaphragm case 12, there being a recess 12^a and an opening 12^b in the bottom of the said case. Resilient insulating rings 13 fit within the recess 12^a, said rings securely holding a diaphragm 14. A cover 15 fits the case 12 tightly and is secured to the same by screws 16. Screwing into the said cover 15 is a sound tube 15^a. Passing through the center of the diaphragm 14 is a rod 17 held to the said diaphragm by a nut 17^a, the lower end 65 of the rod terminating in an eye 17^b to which is secured one end of a wire 18 whose other end is attached to the wire 5 at 18^a. Surrounding the above mentioned apparatus is a casing 19 which is held to an end- 70 plate 20 by means of screws 19^a, the said end-plate being secured to the magnet 1 by means of screws 20^a. Passing through the end-plate 20 are terminals 21 which are connected to the coil 2 by wires 22. 75 My device is further explained as follows: The wires 5 and 18 are held in tension by the resiliency of the spring 4 and the attraction of the electromagnet. This tension may be adjusted by the screws 10. In like manner, the angle made by the wire 5 with the horizontal plane may be varied by adjusting the nuts 17^a, thereby shortening or lengthening the distance from the wire 5 to the diaphragm 14 and changing the lever- 80 age. It will be readily understood that any slight inward or downward movement given to the armature will cause a change in the angle of the wire 5, thereby causing the wire 18 and the rod 17 to move upward or downward, as the case may be. The said movement of the wire 18 and the rod 17 will, of course, be much greater than the movement of the wire 5 due to the change in the angularity of the wire 5. The movements 85 of the rod 17 are transmitted to the diaphragm 14. 90 From the foregoing it will be seen that by the use of my device small movements of the armature are much amplified in transmission through the diaphragm, and that the amount of movement may be changed by simply varying the angle which the wire 5 makes with respect to the horizontal plane. It is also clear that the above mentioned 100 amplified movements of the diaphragm are accomplished without the use of levers in the usual sense of the word, as is common in the art, and the movements of all the parts of my device are accomplished with a 105 110

minimum of friction and inertia, due to the extreme lightness of the parts and to the peculiar arrangement of the same.

I have shown a particular form of embodiment of my invention but am aware that many minor changes therein will readily suggest themselves to others skilled in the art without departing from the spirit and scope of the invention, and I therefore desire to avoid being limited to the exact form shown and described except as defined by the appended claims.

What I claim as new and desire to protect by Letters Patent is—

15. 1. In a telephone receiver including a supporting frame, diaphragm and magnets, the combination of means for amplifying the vibrations of the diaphragm in varying degree, the said means including an adjusting screw and a flexible connection between the same and the armature of the magnet, a spring which normally tends to hold the said armature against the poles of the magnet, and a second flexible connection between 20 the diaphragm and the first mentioned flexible

connection and means for adjusting the said second flexible connection whereby the first mentioned flexible connection is changed to varying degrees of angularity with respect to the horizontal.

2. In a telephone receiver including a supporting frame, diaphragm and magnets, the combination of means for amplifying the vibrations of the diaphragm in varying degrees, the said means including an adjusting screw in the supporting frame, a flexible connection between said screw and the armature of the magnet, a second flexible connection between the first mentioned flexible connection and the diaphragm, and adjusting nuts therefor, a leaf spring having a slot through which the first mentioned flexible connection passes, the said leaf spring having one of its ends adjustably mounted upon the supporting frame and its free end 35 in contact with the armature.

PAUL J. HACKETT.
